UNITED STATES PATENT OFFICE.

CHARLTON MESSICK, OF ST. LOUIS, MISSOURI.

TRANSPORTATION-TICKET.

1,121,109.

Specification of Letters Patent. Patented Dec. 15, 1914.

Application filed May 17, 1912. Serial No. 697,931.

To all whom it may concern:

Be it known that I, CHARLTON MESSICK, a citizen of the United States, and a resident of the city of St. Louis and State of Missouri, have invented a new and useful Improvement in Transportation-Tickets, of which the following is a specification:

My invention relates to the so-called scrip or mileage books, which comprise a cover inside of which is folded a long strip of paper having printed thereon a series of numbered marks extending in a series longitudinally thereof. These marks represent units of money or mileage, as the case may be; and a portion of the strip comprising the required number of units is detached either by the conductor, when the same is good for transportation, or by the ticket agent in exchange for a passage ticket, according to the requirements of the carrier. Each of these methods of use has certain advantages and certain disadvantages; and it is the purpose of the present invention to combine the advantages of both methods and at the same time eliminate the principal disadvantages of each.

My invention is hereinafter described and claimed.

In the accompanying drawing which forms part of this specification and wherein like symbols refer to like parts wherever they occur, Figure 1 is a perspective view of a "book" conforming to my invention, and showing a portion of the units strip completed as a passage ticket and detached from the book; and Fig. 2 shows a modified form of a completed passage ticket and the end portion of the units strip from which it is detached.

The construction illustrated in Fig. 1 is a "book" comprising a cover 1 and an elongated strip 2 of paper pasted or otherwise secured at one end to said cover and folded to fit therein. Along each side margin of the strip is printed a scale or series of marks 3, 4 at equal distances to indicate units of money or mileage. The strip also has printed thereon a series of consecutive numerals 5 extending the full length of the strip. Also extending the full length of the unit strip 2 and arranged in two parallel rows are repetitions of certain identification

data such as a certain letter or letters and a certain numeral. The letter or letters are usually the initials of the name of the carrier issuing the book, and the numeral on the strip is usually the number of that particular strip in the total issue; and enough of the identification data, for instance, the numeral, thereof, is printed on the cover. 55 In the case of the particular strip illustrated in Fig. 1 of the drawing, the letter M is the identification letter or initial that is repeated at frequent intervals, and the number 100 is the identification numeral that is likewise repeated. 60 65

Extending the full length of the strip 2 substantially midway between the sides thereof, is a line 6 of scoring or perforations, whereby the strip is separable lengthwise 70 into sections, whose respective uses may be suitably indicated and which are hereinafter referred to as the accounting section or "stub" section 7 and the passage section 8. This line of scoring or perforations lies between the parallel rows of repetitions of the identification data; and consequently each longitudinal section of the ticket contains the same scale and the same serial repetition of identification letter and number. This 75 duplication of scale and identification data is hereinafter referred to by the term "duplex."

My invention contemplates that the end portion of the passage section of the duplex 85 strip shall be validated by the ticket agent to convert the same into a passage ticket. For this purpose, the ticket agent will detach from the end of the accounting section of the duplex strip the number of units required for the particular trip; and then he will write on the corresponding portion of the passage section the name of the place of destination and then imprint thereon his official stamp 10 bearing the name of the 95 place of origin, name of the carrier and the date of validation. The portion of the passage section thus validated may be either left integral with the main strip or detached by the ticket agent, according as the regulations of the carrier may require. If left by the ticket agent integral with the main strip, it will be detached by the conductor. It is preferable to leave an imprinted space 11

extending longitudinally of the ticket to receive the signature of the passenger in case it is required by the regulations of the carrier.

5. The more important advantages of this invention are the following: It dispenses with the necessity for a large stock of printed tickets as required by present practice, as one section of the end portion of the 10 units strip is converted into a passage ticket by the act of the ticket agent, and the other section of the duplex end portion serves as a self-checking stub therefor. In the next place, as the detachment is made by the 15 ticket agent, it saves the time of the conductor and is more likely to be effected without error than is feasible when the detachment is left to the conductor. Besides, it guards against dishonesty on the part of the 20 conductor in detaching too small a portion of the strip through collusion with the passenger. Also, it dispenses with the more or less complicated work of the ticket agent necessary for a proper accounting; because 25 the conductor is required to take up and return to the accounting department the ticket as validated by the agent, and, therefore, the agent need only return to the accounting department the corresponding 30 "stub" or duplicate section of the end portion of the duplex strip which "stub" was detached by him for the purpose.

The construction illustrated in Fig. 2 embodies my invention in a form adapted for 35 the use of the several carriers belonging to an association interchangeably. This form comprises the same elements as those illustrated in Fig. 1; but it also comprises, in addition, a third section 12 extending the 40 full length of the units strip. This third section is hereinafter referred to as the "bureau" section and is preferably the middle one of the three, being separated from the accounting section on one side and from 45 the passage section on the other by lines 6 of perforations or scorings so as to be easily severed therefrom. This bureau strip takes care of the business with the bureau or association in like manner as described above 50 with reference to the accounting strip, the difference being that the detachments from the accounting strip are forwarded by the ticket agent to the auditor or accounting department of his own company, whereas 55 the detachments made by the conductor from the bureau section are forwarded by him to the bureau or association. Such detachments are substantially identical and constitute in effect self-checking stubs for 60 the passage ticket.

What I claim is:—

1. A ticket of the kind described comprising a strip having a line of perforations or the like extending longitudinally thereof 65 and separating the strip into sections suit-

ably indicated for accounting and for passage, the endmost portion of the passage section having thereon the name of the place of destination and the stamp of the place of origin so as to constitute a passage ticket, substantially as and for the purpose described.

2. A ticket of the kind described comprising a strip having a scale extending lengthwise thereof and having a line of perforations or equivalent devices extending lengthwise thereof and separating the strip into sections suitably indicated for accounting and for passage section, the endmost portion of the passage section having thereon the name of the place of destination and the stamp of the place of origin so as to constitute a passage ticket, substantially as and for the purpose described.

3. A ticket of the kind described comprising a strip having a line of perforations or the like extending longitudinally thereof and separating the strip into an accounting section and a passage section, the endmost portion of said passage section being validated to constitute a passage ticket and the corresponding portion of the accounting section constituting a self-checking stub for said ticket, substantially as and for the purpose described.

4. A ticket of the kind described comprising a cover and a strip folded therein and having a line of perforations extending the full length thereof to divide it into an accounting section and a passage section, 100 each of said sections having a continuously marked scale extending lengthwise thereof, and each of said sections and said cover having certain identification marks in common, the endmost portion of the passage section being provided with data to constitute a passage ticket, and the corresponding portion of the accounting section constituting a self-checking stub thereof.

5. A ticket of the kind described comprising a cover and a strip having a serially numbered scale extending lengthwise thereof, said strip having lines of perforations or the like extending lengthwise thereof to divide the same into a passage section, an 110 accounting section and a bureau section, all suitably indicated, said cover having certain identification data, and the same data being repeated at intervals along each of said sections.

6. In a ticket, the combination of a continuous mileage or scrip strip and a suitably indicated trip passage ticket section separably connected along the side thereof.

7. In a ticket, the combination of a continuous scrip or mileage strip, and a suitably indicated trip passage ticket section and a self-checking accounting section separably connected to said continuous strip.

8. A ticket comprising a continuous strip

having a plurality of separable portions each having identification marks thereon in common, the endmost portion of said strip alone bearing thereon the designation of the 5 place of destination and the authentication mark of the initial point.

Signed at St. Louis, Missouri, this 15th day of May, 1912.

CHARLTON MESSICK.
